UNITED STATES PATENT OFFICE.

CHARLES D. BRANDT, OF RICHMOND HILL, NEW YORK, ASSIGNOR OF ONE-HALF TO
EUGENE J. SCHWEIZER, OF RIDGEWOOD, NEW YORK.

PUMP.

1,356,255.

Specification of Letters Patent.

Patented Oct. 19, 1920.

Application filed December 6, 1919. Serial No. 342,882.

To all whom it may concern:

Be it known that I, CHARLES D. BRANDT, a citizen of the United States and resident of Richmond Hill, borough and county of 5 Queens, city and State of New York, have invented certain new and useful Improvements in Pumps, of which the following is a specification.

My invention relates to devices including 10 a cylinder and a manually actuated reciprocating plunger which for convenience of description I refer to as pumps and which find their duplicate, so far as construction is concerned, in grease and oil guns and the 15 like. In devices of this character the cylinder is generally connected at least at one end with a base or its equivalent in the form of caps or the like, by means of screw-threads which constitute a relatively high 20 priced and unsatisfactory connection. The object of my invention is to provide a novel arrangement whereby the cylinder and the base or its equivalent are connected in a simple and efficient manner and whereby 25 the cost of production is materially reduced. My invention will be fully described herein- after and its features of novelty will be pointed out in the appended claim.

For the purpose of illustrating the invention and without intending to define its limits, I have shown a specific embodiment of the invention applied to a pump of the type commonly used for inflating pneumatic tires. In said drawings, Figure 1 is an elevation of the pump, partly in section; Figs. 2 and 3 are detail sectional views showing the pump at different stages of its development; Fig. 4 is a cross-section thereof on the line 4-4 of Fig. 1; and Figs. 5 and 6 40 are plan and sectional views respectively of the locking element included in the device.

In the illustrated example, 5 represents the cylinder or barrel of a conventional hand pump and 6 designates the piston or 45 plunger carried by the stem 7 and reciprocable in said cylinder 5 by means of the handle 8 or its equivalent. It will be understood that the pump includes the customary inlet and discharge connections and that 50 these have not been shown in detail as they form no part of the present invention; the discharge port is indicated at 5^a in Fig. 1. The one end of the cylinder 5 projects into tubular neck 9 of the base 10 and is formed

with an enlargement 11 which fits within 55 a complementary recess 12 comprising a continuation of the axial bore 13 of the neck 9. With this arrangement coöoperating annular shoulders 14 and 15 are provided respectively in the neck 9 and on the cylinder 60 5 and serve to prevent separation of the latter from the base 10 in an axial direction. The locking element whereby the cylinder 5 and neck 9 are locked positively together against relative rotation or other relative 65 movement comprises a disk or washer 16 which snugly fits within the enlargement 11 and lies against the closed inner end of the neck 9.

The base 10 with the neck 9 and its axial 70 bore 13 and continuing recess 12 may be produced in any suitable manner as by casting, it being understood that the diameter of the bore 13 is such as to snugly fit about the cylinder 5 when the latter is connected 75 with the base 10.

To combine the cylinder 5 and the base 10 the one end of said cylinder is inserted into the bore 13 and moved axially thereof to the position illustrated in Fig. 2. By 80 means of suitable mechanism the end of the cylinder 5 is expanded into the recess 12 until it firmly engages the wall of the latter, and to form the shoulder 14 in firm surface engagement with the shoulder 15 85 as shown in Fig. 3. After this has been done, the locking disk or washer 16 which at this stage is dished, as illustrated in Fig. 6 and of a diameter to readily pass through the cylinder 5 is dropped into the recess 12 90 within the enlargement 11 as indicated in Fig. 3. As a final step this dished disk or washer 16 is flattened out in any suitable manner so that its periphery engages the inner surface of the enlargement 11 and 95 maintains it securely in position therein as shown in Fig. 1. It will be understood that the dimensions of the disk or washer 16 are so computed that in its fully flattened condition it will itself be rigidly secured within 100 the enlargement 11 and will exert a clamping force in directions transverse to its axis whereby the cylinder end and neck 9 are rigidly fastened together against relative movement in all directions including rotation. 105

The device is simple and easy to fabricate and requires no expensive treatment of the

elements to effect a connection; at the same time the union between the elements is of maximum efficiency as to holding power and is not disturbed by any rotative or other movements for instance of the piston relatively to the cylinder as is the case where the parts are connected by screw-threading.

I have described my invention in connection with a pneumatic tire pump because it 10 is particularly adapted to this form of device; it will be understood however that the elements of the illustrated embodiment find their duplicates in grease and oil guns and kindred devices and that the invention 15 is equally well adapted to such devices.

Various changes in the specific form shown and described may be made within the scope of the claim without departing from the spirit of my invention.

I claim:

In a pump, the combination of a base, a neck projecting from said base and provided with an axial bore and a continuing recess of larger diameter whereby an annular shoulder is formed between said bore and recess, a pump cylinder fitted within said bore, an annular shoulder forming a continuation of said cylinder and fitted against the annular shoulder of said neck, an enlargement forming a continuation of said cylinder shoulder and fitted within said recess and a disk within said enlargement effective in directions transverse to the axis of said cylinder to clamp the enlargement against the wall of said recess.

In testimony whereof I have hereunto set my hand.

CHARLES D. BRANDT.
